UNITED STATES PATENT OFFICE.

GEORGE C. BEIDLER, OF OKLAHOMA, OKLAHOMA.

PHOTOGRAPHING AND DEVELOPING APPARATUS.

1,153,017.

Specification of Letters Patent.

Patented Sept. 7, 1915.

Application filed February 3, 1909. Serial No. 475,791.

To all whom it may concern:

Be it known that I, GEORGE C. BEIDLER, a citizen of the United States of America, residing at Oklahoma, in the county of Oklahoma and State of Oklahoma, have invented certain new and useful Improvements in Photographing and Developing Apparatus, of which the following is a specification.

This invention relates to a photographic and developing apparatus and particularly to a reproducing machine by which drawings, printed and written documents, and records may be photographed.

An object of this invention is to produce a machine having a supply of sensitized material, preferably of film, wound on a roll and adapted to be unwound therefrom for the purpose of exposing the film to light, and in combination therewith, novel means for severing the film after it has been exposed and developed.

A further object of the invention is to produce a machine of the character noted having means for supplying film to be exposed and means for exposing said film as well as a novel receptacle for containing developer in operative relation to means for exposing the film to light and means for drawing the film through the receptacle.

Furthermore, an object of the invention is to provide a receptacle for the developer and a drain pan associated with the receptacle, means being provided for detachably holding the receptacle in the pan; the pan and receptacle being incased but applied to the casing in such a way that they may be removed for the purpose of repair or for the purpose of cleaning the receptacles.

A further object of the invention is to produce a machine having a pan containing fixing fluid, said pan being provided with a hood secured to the casing; the casing being provided with a support for the pan, which pan is in position to receive the severed developed films after they are projected from the casing.

A further object of this invention is to produce a novel cutting mechanism in which a stationary and a movable knife are employed, the said movable knife having a yieldable pivot in order that it may adjust itself with relation to the stationary knife, means being also provided for reciprocating the movable knife and exerting pressure thereon laterally.

With the foregoing and other objects in

view, the invention consists in the details of construction and in the arrangement and combination of parts to be hereinafter more fully set forth and claimed.

In describing the invention in detail, reference will be had to the accompanying drawings forming part of this specification, wherein like characters denote corresponding parts in the several views, in which—

Figure 1, illustrates a side elevation of a photographing and developing apparatus embodying the invention; Fig. 2, illustrates a longitudinal, vertical sectional view through the developing tank and fixing pan, a fragment of the bellows and magazine being shown; Fig. 3, illustrates a perspective view of a movable knife and the means for operating it; Fig. 4, illustrates a view in elevation of the side of the developer tank, partly broken away to show a drum, said view also illustrating the bracket for supporting the drum and the gearing for the feed rollers; Fig. 5, illustrates a sectional view of the bellows showing the application of the ground glass thereto for the purpose of obtaining proper focus; Fig. 6, is a detail view of the pivot for the movable knife, a fragment of said knife being shown in plan; Fig. 7, illustrates a view in elevation of the stationary and movable knives having means connected to the movable knives for imparting motion to one of the feed rollers; and Fig. 8, is a detail view of the ratchet wheel and parts operating therewith. Fig. 9 is a detail sectional view of the feeding rollers, a tension device being shown in them. Fig. 10 is a view in elevation of a bracket.

In these drawings A, denotes a bellows having a lens box B, and a lens C. The lens box is here shown as in position to operate in conjunction with a horizontally disposed supporting table (not shown) adapted to contain copy for the material to be photographed, but as the means for supporting the copy is an immaterial detail of construction, it is not illustrated. The bellows frame D, has a stud E, on each side adapted to engage a hook D' or the like by which the casing F, is held in operative relation to the said bellows frame.

The developing apparatus which is designed to act in conjunction with the bellows, bellows frame, and lens, has a suitable base G, which is preferably rigid with the bellows frame, and the casing F, is sup-

ported by the base and is held in operative relation thereto by means of hooks H, which engage screws or studs I.

The casing F, contains the magazine f, which is provided with bearings such as F' for a core J, of a roll of sensitized material, and the said sensitized material is drawn from the roll and through an opening F' between the casing and the bellows frame in order that the said sensitized material may be exposed to light as it passes from the magazine to the developing tank. The casing, furthermore, has a partition K, therein forming the bottom of the magazine and said partition has a bracket L, secured to it near one end.

The side walls of the casing at their lower edges are provided with brackets M, having apertures Z' to receive the journals N, of the drum O, hence when the casing is removed from the base and bellows frame, the drum is removed with it. Each bracket M, is provided with an elongated bearing designed to receive the shaft P, of the upper feed roller Q. The shaft P, is further mounted in an arm R, at each end, each arm R, being pivotally mounted on a pin or stud S, projecting from the inner surface of a bracket M. In order to hold the arm R, and the shaft P, normally depressed, a spring T, has a looped portion encircling the stud S, and one extremity of said spring bears on the shaft P, whereas the other extremity t, of said spring is anchored to the bracket M, hence it is by this construction that the feed roller Q, is moved with relation to the feed roller U, which feed roller U, is secured to a shaft u. The shaft P extends through one of the brackets M and the shaft u extends through the ends of the tank Y as shown in Fig. 4. The shafts P and u are provided with gear wheels V and v, respectively, and the lower shaft u, projects beyond the side of the casing and has a crank W, thereon, by which the shaft is rotated. The sensitized element, viz., paper or the like, is shown at X, and it will be observed that it passes around the drum O, and between the rollers Q and U, and that by turning the crank W, the sensitized element is drawn from the magazine, past the exposing chamber and into the tank Y.

The tank Y, is designed to contain a developing fluid and is preferably U-shaped in cross section and is provided with a support Z, at each end, said support having a foot z, with an aperture to receive a stud z', which projects from the bottom of the drip pan Z'. The drip pan has a depending tube Z', extending through an aperture in the bottom of the base, in order that drippings from the sensitized element may be discharged from the interior of the apparatus. It is to be understood that the stud z', is provided for the feet of the support of

the tank remote from the bellows side of the casing and as shown in Fig. 2, the upper edge of the side wall of the tank lies under a bracket 8, secured to the bellows frame. In practice I utilize two of these brackets 8, 70 one near each end of the tank and they act as braces to prevent movement of the tank, especially as the feet of said tank are well anchored through the medium of the studs z'. 75

I have found it desirable to sever the sensitized element after it has been exposed and developed and to deliver the severed portions of the sensitized elements to a pan 9, containing a fixing fluid. The wall of the 80 casing is cut away to form an opening 10, through which the sensitized element is projected into the pan 9.

The cutting apparatus is mounted in conjunction with the bracket L, which has a 85 sleeve 11, extending therefrom, the said sleeve being in line with an aperture formed in the bracket, which aperture and sleeve are designed to receive the pivot 12, on which the movable knife 13, is mounted and 90 secured. The pivot 12, is provided with a collar 14, and a spring 15, interposed between the collar and the end of the sleeve, which spring acts to hold the pivot normally projected rearwardly, and the inner end of 95 said pivot is provided with a head 16, bearing against the knife 13, which is apertured to receive the pivot. The action of the spring 15, is, therefore, to draw the movable knife toward the stationary knife 100 17, which stationary knife is mounted on the lower end of the bracket L. The sleeve 11, is provided with a diagonally disposed slot 18, and the pivot 12, has a pin 19, riding on the edge of the diagonally disposed 105 slot 18, the camming action of which causes the pivot to move longitudinally in its bearings against the action of the spring 15, in order that the movable knife may be permitted to clear the edge of the stationary 110 knife.

In order to operate the movable knife, an arm 20, is applied to a recess 21, of said movable knife near the end opposite the pivot and said arm 20, projects from a collar 22, secured to a shank 23, of an oscillating handle 24, and the shank 23, is movable in one end of the casing. The outer extremity of the arm has an angular portion 20°, which acts as a cam for the movable 120 knife and presses it downward toward the stationary knife, while moving its cutting edge past the stationary knife, that is to say the said arm will impart to the movable knife a lateral pressure tending to force it against the cutting edge of the stationary knife, thus insuring proper action of the knives in operation. Owing to the lateral pressure imparted to one end of the knife 125 by the arm and the movement given to the 130

pivot of the knife by the cam on the sleeve which permits the pivoted end to move slightly in a direction opposite to that imparted to the outer end of the knife by the 5 arm, the knife has what might be termed a slight oscillatory motion with relation to the stationary knife and the stationary knife would act as a fulcrum for the pivoted knife. Unusual pressure is, therefore, applied to the contacting surfaces of the 10 knives and positive cutting action is insured. After a film has been severed by a complete stroke of the knife, the pivot of the knife is retracted by the spring on the 15 pivot as the knife swings upwardly under the influence of the spring 25. The movable knife is held normally elevated through the medium of the spring 25, which is secured to a screw 26, in said knife and to a 20 screw 27, in the partition K, hence the said arm 20, operates the knife against the action of the said spring.

I have found in practice that when a sensitized element such as paper becomes wet, 25 it has a tendency to buckle and owing to the fact that the movable knife is pivoted at one end with relation to the stationary knife, the space between the knives near the pivot of the movable knife is rather restricted 30 and hence, when the sensitized element buckles, it is apt to abut the movable knife when the feed rollers are manipulated and when this occurs, the operation of the apparatus is impaired. There are several ways 35 of obviating this difficulty, one of which is to have the knives slightly longer than they are actually required to be for severing the film in which event the restricted opening between the two knives is removed from the 40 edge of the sensitized element, and another way is to impart to the sensitized element a slight projecting movement immediately after a print has been cut therefrom, thus causing the end of the sensitized element to 45 pass beyond the cutting edge of the knife for any buckling thereafter would not affect the operation of the apparatus.

As a means for carrying into effect this latter idea for projecting the end of the 50 sensitized element, I may extend the shaft P', in the opposite direction to that having the crank and provide it with a ratchet wheel 28. I then pivotally mount on the end of the shaft P', an arm 29, carrying a spring 55 pressed dog 30, adapted to engage the teeth of the ratchet wheel. A link 31, is pivotally connected to the arm 29, and said link is connected to a lever 33, pivoted on a bracket 32, which may extend from the partition K, of the casing. The inner end of the lever 32, is connected through the medium of the link 33, with an ear 34, on the knife 35. In the form shown in Fig. 7, the knife 35, is movable and acts in conjunction 60 with the stationary knife 36. In this form,

an arm 37, similar to the arm 20, is used for the purpose of actuating the movable knife.

As shown in Fig. 5, the apparatus is focused by applying to the bellows frame D, having the bracket 8, a ground glass 39, in 70 a suitable frame 38, and in order to apply the ground glass frame, it is necessary to displace the removable section of the casing.

The operation of the apparatus will be as follows: The proper focus having been 75 attained and the casing having been applied to the base, the feed roller P, removed with the casing will be restored to its operative relation to the feed roller U. The sensitized element will then be in position 80 between the two rollers and when motion is communicated to the lower roller through the medium of the crank, the said rollers will be driven in unison through the medium of the gearing V and v, thus a positive feeding action will result and as the 85 springs I, press the two rollers together, sufficient friction is produced between the rollers and the sensitized element to insure positive feeding action of the said sensitized 90 element. After the sensitized element has been exposed and drawn into the developing tank and is acted on by a chemical therein, it is projected between the knives and through the opening in the casing to the 95 pan 9. When a given length of the sensitized element has passed between the knives, the knife operating mechanism is pressed so that the sensitized element is severed, the severed length finding its way into the pan 100 9, containing the fixing fluid. In order to prevent light from gaining access to the pan 9, the said pan is provided with a hood 39, which may be of any well known construction, but it is preferably of the construction shown herein and specifically claimed in a companion application filed by me July 10, 1908, Serial Number 442,877, and as said hood is fully described in said application, it will not be described in detail here. 105

When the apparatus shown in Fig. 7, is employed in connection with the knives, it follows that when the pivoted knife descends, the lever 32, will be oscillated on its pivot and the arm 29, will be moved to carry the dog 30, into engagement with teeth in advance of the one engaged by it as shown in Fig. 8. After the knife has descended the full stroke and the knife operating mechanism is released, the spring 25^a, will elevate the knife and oscillate the lever 32, in order to carry the arm 29, back to the position in which it is shown in Fig. 7, and with the return of the arm to said position, the ratchet wheel 28, will be partially rotated, and hence the shaft P', will partially rotate and communicate motion to the feed roller thereof and to the companion feed roller 125 acting in conjunction with it, and thus the 130

edge of the sensitized element will be carried beyond the knife and the sensitized element will be free of any obstruction when power is again applied to the feed rollers.

5 The casing has an opening in front in communication with the bellows and after the sensitized element comes to rest in the opening, it may be exposed to light. The opening is also provided with a guide which 10 is attached to the side edges of the opening, and the said walls of the opening are further provided with slots to receive a dark slide.

I claim—

15 1. In a photographing and developing apparatus, a casing comprising a stationary and a removable section, the removable section containing a supply of film and having means for exposing the film to light, a tank 20 designed to contain developer inclosed by the casing, a roller journaled in the tank, a member mounted to rotate in the tank, a feed roller having yieldable bearings associated with the removable section of the casing 25 and coacting with the first mentioned roller, means for yieldingly holding the second roller in contact with the first mentioned roller, and means for rotating the rollers in unison whereby film may be drawn 30 around the member.

2. In a photographing and developing apparatus, a casing comprising a stationary and a removable section, the said removable section containing a magazine designed to 35 contain a supply of film, associated with means for exposing said film to light, brackets extending from the removable section of the casing, a tank in the stationary section of the casing for containing developer, a 40 member mounted in the brackets and rotatable in the tank, a feed roller journaled in the tank, a second feed roller having a shaft journaled in the bracket of the removable section, arms in which the shaft of the roller 45 is mounted, said arms being pivotally held in position, means for yieldingly holding one roller in contact with the other roller, and means for rotating the rollers in unison whereby film may be drawn around the 50 member and projected from the casing.

3. In a photographing and developing apparatus, a casing comprising a stationary and a removable section, the said removable section containing a magazine designed to 55 contain a supply of film, associated with means for exposing said film to light, brackets extending from the removable section of the casing, a tank in the stationary section of the casing for containing developer, a 60 member mounted in the brackets and rotatable in the tank, a feed roller journaled in the tank, a second feed roller having a shaft journaled in the bracket of the removable section, arms in which the shaft of the roller 65 is mounted, said arms being pivotally held

in position, means for yieldingly holding one roller in contact with the other roller, a drip pan under the tank, and a drain for the drip pan.

4. In a photographing and developing apparatus, a casing comprising a stationary and a removable section, the said removable section containing a magazine designed to contain a supply of film, associated with means for exposing said film to light, brackets extending from the removable section of the casing, a tank in the stationary section of the casing for containing developer, a member mounted in the brackets and rotatable in the tank, a feed roller journaled in the tank, a second feed roller having a shaft journaled in the bracket of the removable section, arms in which the shaft of the roller is mounted, said arms being pivotally held in position, means for yieldingly holding one 70 roller in contact with the other roller, a drip pan under the tank, a drain for the drip pan, 75 supports for the tank, and means for anchoring the supports to the drip pan.

5. In a photographing and developing apparatus, a casing comprising a stationary and a removable section, the removable section containing a supply of film and having means for exposing the film to light, a tank designed to contain developer inclosed by the casing, a drip pan, supports for the tank standing in the drip pan, and studs in the drip pan, the said supports for the tank having apertures to receive the studs of the drip 90 pan, 95

6. In a photographing and developing apparatus, a casing comprising a stationary and a removable section, the removable section containing a supply of film and having means for exposing the film to light, a tank 100 designed to contain developer inclosed by the casing, a drip pan, supports for the tank standing in the drip pan, studs in the drip pan, the said supports for the tank having apertures to receive the studs of the drip 105 pan, and brackets for engaging the upper edge of the tank for preventing tilting of the said tank.

7. In a photographing and developing apparatus, a casing comprising a stationary and a removable section, the said removable section containing a magazine designed to contain a supply of film, associated with means for exposing said film to light, brackets extending from the removable section of the casing, a tank in the stationary section of the casing for containing developer, a member mounted in the brackets and rotatable in the tank, a feed roller journaled in the tank, a second feed roller having a shaft journaled in the bracket of the removable section, arms in which the shaft of the roller is mounted, said arms being pivotally held in position, means for yieldingly holding one roller in contact with the other 115 120 125 130

roller, means for rotating the rollers in unison whereby film may be drawn around the member and projected from the casing, and means to which the film is delivered by 5 the film moving means for severing the film.

8. In a photographing and developing apparatus, a casing comprising a stationary and a removable section, the said removable section containing a magazine designed to 10 contain a supply of film, associated with means for exposing said film to light, brackets extending from the removable section of the casing, a tank in the stationary section of the casing for containing developer, a drum mounted in the brackets and rotatable in the tank, a feed roller journaled in the tank, a second feed roller having a shaft journaled in the bracket of the removable section, arms in which the shaft of the 15 roller is mounted, said arms being pivotally held in position, means for yieldingly holding one roller in contact with the other roller, means for rotating the rollers in unison whereby film may be drawn around the drum and projected from the casing, and means to which the film is delivered by the film moving means for severing the film, said means for severing the film comprising a stationary and a movable knife.

30 9. In a photographing and developing apparatus, a casing comprising a stationary and a removable section, the said removable section containing a magazine designed to contain a supply of film, associated with 35 means for exposing said film to light, brackets extending from the removable section of the casing, a tank in the stationary section of the casing for containing developer, a drum mounted in the brackets and rotatable 40 in the tank, a feed roller journaled in the tank, a second feed roller having a shaft journaled in the bracket of the removable section, arms in which the shaft of the roller is mounted, said arms being pivotally held in 45 position, means for yieldingly holding one roller in contact with the other roller, means for rotating the rollers in unison whereby film may be drawn around the drum and projected from the casing, means to which the film is delivered by the film moving means for severing the film comprising a stationary and a movable knife, and means for oscillating the movable knife and imparting pressure laterally thereof.

55 10. In a photographing and developing apparatus, a casing comprising a stationary and a removable section, the said removable section containing a magazine designed to contain a supply of film, associated with 60 means for exposing said film to light, brackets extending from the removable section of the casing, a tank in the stationary section of the casing for containing developer, a drum mounted in the brackets and 65 rotatable in the tank, a feed roller journaled

in the tank, a second feed roller having a shaft journaled in the bracket of the removable section, arms in which the shaft of the roller is mounted, said arms being pivotally held in position, means for yieldingly holding one roller in contact with the other roller, means for rotating the rollers in unison whereby film may be drawn around the drum and projected from the casing, means to which the film is delivered by the 70 film moving means for severing the film comprising a stationary and a movable knife, means for oscillating the movable knife and imparting pressure laterally thereof, and a longitudinally yieldable pivot for the 75 movable knife.

11. In a photographing and developing apparatus, a casing comprising a stationary and a removable section, the removable section containing a supply of film and having 80 means for exposing the film to light, a tank designed to contain developer inclosed by the casing, a drum mounted to rotate in the tank, means for drawing the film around the drum and projecting it from the casing, means to which the film is delivered for severing the film comprising a stationary and movable knife, and means for oscillating the movable knife.

12. In a photographing and developing 85 apparatus, a casing comprising a stationary and a removable section, the removable section containing a supply of film and having means for exposing the film to light, a tank designed to contain developer inclosed by 90 the casing, a drum mounted to rotate in the tank, means for drawing the film around the drum and projecting it from the casing, means to which the film is delivered by the film moving means for severing the film 95 comprising a stationary and a movable knife, a longitudinally movable pivot for the knife, and means for oscillating and imparting lateral motion to the movable knife.

13. In a photographing and developing 100 apparatus, a casing comprising a stationary and a removable section, the removable section containing a supply of film and having means for exposing the film to light, a tank designed to contain developer inclosed by 105 the casing, a drum mounted to rotate in the tank, means for drawing the film around the drum and projecting it from the casing, means to which the film is delivered by the film moving means for severing the film 110 comprising a stationary and a movable knife, a bracket, a sleeve thereon having a diagonally disposed slot, a pivot for the movable knife rotatable in the sleeve, a pin 115 projecting from the pivot and movable in the slot in engagement with the sleeve whereby a camming action results, and yielding means for holding the pivot against movement in one direction.

14. In a photographing and developing 120 apparatus, a casing comprising a stationary and a removable section, the removable section containing a supply of film and having means for exposing the film to light, a tank designed to contain developer inclosed by 125 the casing, a drum mounted to rotate in the tank, means for drawing the film around the drum and projecting it from the casing, means to which the film is delivered by the film moving means for severing the film comprising a stationary and a movable knife, a bracket, a sleeve thereon having a diagonally disposed slot, a pivot for the movable knife rotatable in the sleeve, a pin projecting from the pivot and movable in the slot in engagement with the sleeve whereby a camming action results, and yielding means for holding the pivot against movement in one direction.

apparatus, a casing comprising a stationary and a removable section, the removable section containing a supply of film and having means for exposing the film to light, a tank designed to contain developer inclosed by the casing, a drum mounted to rotate in the tank, means for drawing the film around the drum and projecting it from the casing, means to which the film is delivered by the film moving means for severing the film comprising a stationary and a movable knife, a bracket, a sleeve thereon having a diagonally disposed slot, a pivot for the movable knife rotatable in the sleeve, a pin projecting from the pivot and movable in the slot in engagement with the sleeve whereby a camming action results, a spring encircling the pivot engaging the end of the sleeve, and a collar on the pivot forming an abutment for the opposite end of said spring.

15. In a photographing and developing apparatus, a casing comprising a stationary and a removable section, the removable section containing a supply of film and having means for exposing the film to light, a tank designed to contain developer inclosed by the casing, a member mounted to rotate in the tank, means for drawing the film around the member and projecting it from the casing, means to which the film is delivered by the film moving means for severing the film, and a hooded pan adapted to contain fixing fluid into which the film is delivered.

16. In a photographing and developing apparatus, a casing comprising a stationary and a removable section, the removable section containing a supply of film and having means for exposing the film to light, a tank designed to contain developer inclosed by the casing, a member mounted to rotate in the tank, feed rollers for drawing the film through the developing tank, means for rotating the feed rollers in unison, means to which the film is delivered by the film moving means for severing the film, and means actuated by the film severing means for imparting motion to the feed rollers after the film is severed.

17. In a photographing and developing apparatus, a casing comprising a stationary and a removable section, the removable section containing a supply of film and having means for exposing the film to light, a tank designed to contain developer inclosed by the casing, a member mounted to rotate in the tank, feed rollers for drawing the film through the developing tank, means for rotating the feed rollers in unison, means to which the film is delivered by the film moving means for severing the film comprising a stationary and a movable knife, means for actuating the movable knife, and connections whereby the movable knife imparts motion to the feed rollers for projecting the

film beyond the cutting edge of the movable knife.

18. In a photographing and developing apparatus, a casing comprising a stationary and a removable section, the removable section containing a supply of film and having means for exposing the film to light, a tank designed to contain developer inclosed by the casing, a drum mounted to rotate in the tank, feed rollers for drawing the film through the developing tank, means for rotating the feed rollers in unison, means to which the film is delivered by film moving means for severing the film comprising a stationary and a movable knife, a lever operated by the movable knife, a ratchet wheel connected to move one of the feed rollers, and means whereby the lever actuates the ratchet.

19. In a photographing and developing apparatus, a casing comprising a stationary and a removable section, the removable section containing a supply of film and having means for exposing the film to light, a tank designed to contain developer inclosed by the casing, a drum mounted to rotate in the tank, feed rollers for drawing the film through the developing tank, means for rotating the feed rollers, means for severing the film comprising a stationary and a movable knife, a lever operated by the movable knife, a ratchet wheel connected to move one of the feed rollers, and means whereby the lever actuates the ratchet.

20. In a photographing and developing apparatus, a casing comprising a stationary and a removable section, the removable section containing a supply of film and having means for exposing the film to light, a tank designed to contain developer inclosed by the casing, a drum mounted to rotate in the tank, means for drawing the film around the drum and projecting it from the casing, and means associated with the casing for severing the film.

21. In a photographing and developing apparatus, a casing containing a supply of film and having means for exposing the film to light, a developer tank in the casing, a drum mounted to rotate in the tank, means for drawing the film from the exposing means around the drum and projecting it from the casing, and means for cutting the developed film projected from the casing.

22. In a photographing and developing apparatus, a casing having a compartment for containing a supply of film and having means for exposing film to light, a tank designed to contain developer inclosed by the casing, a drum rotatable in the tank, feed rollers for drawing film to the developing tank and for projecting the film from the casing, and means associated with the casing for cutting the film.

23. In a photographing and developing

- apparatus, a casing having a compartment for containing a supply of film and having means through which the film is drawn in which said film is exposed to light, a tank 5 for containing developer into which the film is delivered from the exposing means, means for drawing film through the tank, and means associated with the casing for severing the exposed and developed section of 10 film.
24. In a photographing and developing apparatus, a casing having a compartment for containing a supply of film and having means for exposing film to light, a tank 15 designed to contain developer inclosed by the casing, a drum in the tank, rollers for drawing film through the exposing chamber and through the tank and for projecting the exposed and developed film from the casing, 20 means for driving the rollers in unison and means associated with the casing for cutting that portion of the film that has been exposed and developed.
25. In a photographing and developing 25 apparatus, a casing comprising a stationary and a removable section, the removable section containing a supply of film and having means for exposing the film to light, a tank designed to contain developer inclosed by 30 the casing, a roller journaled in the tank, a member mounted to rotate in the tank, a feed roller having yieldable bearings associated with removable section of the casing and coacting with the first mentioned roller, 35 means for yieldingly holding the second roller in contact with the first mentioned roller, and means for rotating the rollers in unison whereby film may be drawn around the member.
- 40 26. In a photographing and developing apparatus, a casing comprising a stationary and a removable section, the said removable section containing a magazine designed to contain a supply of film, associated with 45 means for exposing said film to light, brackets extending from the removable section of the casing, a tank in the stationary section of the casing for containing developer, a member mounted in the brackets and 50 rotatable in the tank, a feed roller journaled in the tank, a second feed roller having a shaft journaled in the bracket of the re-
- movable section, arms in which the shaft of the roller is mounted, said arms being pivotally held in position, means for yieldingly holding one roller in contact with the other roller, and means for rotating the rollers in unison whereby film may be drawn around the member and projected from the casing. 55
27. In a photographing and developing apparatus, a casing comprising a stationary and a removable section, the removable section containing a supply of film and having means for exposing the film to light, a tank 60 65 designed to contain developer inclosed by the casing, a member mounted to rotate in the tank, means for drawing the film around the member and projecting it from the casing, means for on the casing severing the film, and a hooded pan adapted to contain fixing fluid into which the film is delivered. 70
28. In a photographing and developing apparatus, a casing comprising a stationary and a removable section, the removable section containing a supply of film and having means for exposing the film to light, a tank 75 80 designed to contain developer inclosed by the casing, a member mounted to rotate in the tank, feed rollers for drawing the film through the developing tank, means for rotating the feed rollers in unison, means for severing the film, and means actuated by the film severing means for imparting motion to the feed rollers after the film is severed. 85
29. In a photographing and developing apparatus, a casing comprising a stationary and a removable section, the removable section containing a supply of film and having means for exposing the film to light, a tank 90 95 designed to contain developer inclosed by the casing, a member mounted to rotate in the tank, means for drawing the film around the member, and projecting it from the casing, and means on the casing for severing the film. 95

In testimony whereof, I affix my signature in the presence of two witnesses.

GEORGE C. BEIDLER.

Witnesses:

J. A. PETTIS,
G. C. KINGDON.
